UNITED STATES PATENT OFFICE.

AUGUSTUS F. HARTER, OF CHICAGO, ILLINOIS.

DESIGN FOR A COOKING-RANGE.

40,272.

Specification for Design. Patented Sept. 21, 1909.

Application filed March 5, 1909. Serial No. 481,554. Term of patent 7 years.

To all whom it may concern:

Be it known that I, AUGUSTUS F. HARTER, a citizen of the United States, residing at Chicago, in the county of Cook and State of Illinois, have invented a new, original, and ornamental Design for Cooking-Ranges, of which the following is a specification, reference being had to the accompanying drawing, forming part thereof.

The figure is a perspective view of a cooking range, showing my new design.

I claim:

The ornamental design for a cooking range, as shown.

AUGUSTUS F. HARTER.
